UNITED STATES PATENT OFFICE

2,085,971

ROAD MACHINE

Carl A. Gustafson, Peoria, Ill., assignor to Caterpillar Tractor Co., San Leandro, Calif., a corporation of California

Application March 19, 1934, Serial No. 716,324

8 Claims. (Cl. 37—110)

Statement of invention

The present invention relates to road machines, and more particularly to the provision of an improved plow construction for elevating graders.

5 It is an object of the invention to provide in an elevating grader, an improved plow construction in which the plow is readily adjusted with respect to the frame of the machine.

10 Another object of the invention is to provide an improved plow construction for elevating graders in which the suction, i. e., the angle of the plow with respect to the ground can be adjusted.

15 Another object of the invention is to provide an improved plow construction for elevating graders which is of a simple yet sturdy design, and which can be manufactured and assembled economically.

20 Other objects will appear as the description progresses.

Description of figures

Fig. 1 is a left side elevation of an elevating grader embodying the improved plow construction of my invention.

25 Fig. 2 is a schematic plan view of the grader.

Fig. 3 is a section taken in the plane of the line 3—3 in Fig. 2.

Fig. 4 is a fragmentary view indicated by the line 4—4 in Fig. 2.

30 Fig. 5 is a fragmentary sectional view taken as indicated by arrows 5—5 in Fig. 1.

Fig. 6 is a fragmentary sectional view taken in the plane of the line 6—6 in Fig. 5.

Description of machine

35 The elevating grader has frame 10 which is supported in any suitable manner on front wheels 11 and rear wheels 12. Carrier 13 has an end positioned below the arched central portion of frame 10 and extends transversely thereof, being supported from frame 10 by a plurality of chains 14 connected to carrier 13 and to shafts 16 on frame 10. Shafts 16 are operated by suitable gear and shaft connections from power control mechanism, 40 including gear box 17 which houses reversible clutch means, controlled by hand levers 18 and driven from engine 19. The drive (not shown) for the endless conveyor or belt is also provided by engine 19.

45 Adjacent the ground or pickup end of carrier 13, plow 21 is provided on a frame of tubular welded construction, which is adjustably connected to and supported from frame 10. The conventional adjustable connections between plow 21 and frame 10 provide for lateral adjustment of

the plow with respect to the pickup end of carrier 13, and for tilting of the plow for bank cutting operations. The adjustable supports for plow 21 provide for vertical adjustment thereof from operative to inoperative position or vice versa, and for adjustment of the suction of the plow, i. e., its angle with respect to the ground.

Plow 21 (Fig. 1) is supported in a conventional manner by bracket 22, vertical plate or standard 23, and brace 24, from plow frame or beam 26. Two sets of longitudinally spaced transverse apertures 27 are provided in beam 26 for cooperation with pins on standard 23 and brace 24, whereby plow 21 can be adjusted to cast material at any desired location transversely of carrier 13.

Plow beam 26 is of tubular construction and is weighted at its rear end to hold plow 21 to its work. Beam 26 (Figs. 1, 2, and 4) includes channel 36 having plate 37 welded between the flanges thereof. At the rear end of beam 26, weight 38 (Fig. 2) is secured therein by means of bolts 39.

Beam 26 is provided with spaced connections to the frame of the machine which are adjustably connected thereto in a conventional manner, to provide for lateral adjustment of plow 21 with respect to carrier 13, and to provide for tilting of the plow outwardly for bank cutting operations. Adjacent the front end and at the lower edge of beam 26, tubular cross member 41 (Fig. 2) has one end pivotally connected to the beam at 42. Cross member 41 extends across under frame 10 and is provided at its other end with spaced apertures 43 adapted to receive pin 44 (Figs. 2 and 3) passing through connecting yoke 45 journaled at its ends in brackets 46 mounted on frame 10. To accomplish tilting of beam 26 with respect to cross member 41, a telescopically adjustable connection is provided therebetween comprising threaded members 51 (Figs. 2 and 4) pivoted to beam 26 and member 41, respectively, and each having threaded engagement within coupling 52. By rotating coupling member 52, beam 26 can be adjusted angularly with respect to cross member 41 to tilt plow 21 outwardly.

Member 41 also serves to transmit the draft in a conventional manner from frame 10 of the machine. Draft chain 61 (Figs. 1 and 2) is pivotally connected at its front end to draft link 62 pivoted on draft bolt 63 in front axle 64. At its rear end, chain 61 is connected to clevis 66 embracing member 41 and secured thereto by bolt 67 passing through one of the plurality of apertures 68 in angle 69 welded to member 41. To prevent longitudinal movement of plow beam 26, chain 71 is secured between standard 23 and frame 10.

Adjacent its rear end, beam 26 has pivotal connection 72 with tubular cross member 73. Cross member 73 extends transversely of frame 10 and at its flat outer end, has spaced apertures 74. Member 73 extends through bracket 76 and is secured thereto by bolt 77 passing through one of apertures 74. Thus it is seen that spaced transverse members are provided for connecting the plow to the frame of the machine, said members being laterally adjustable to accomplish similar adjustment of plow 21, and also allowing for tilting of plow 21 to bank cutting position.

Adjustable lift means are provided for supporting plow 21 from frame 10, comprising spaced lift mechanisms which are selectively operable to accomplish independent adjustment of either end of plow beam 26 to control suction of plow 21. Adjacent its front and rear ends, plow beam 26 (Fig. 1) is connected by resilient couplings 81 to lift chains 82 having their upper ends connected to respective hoist drums 83, 84 on shaft 86. Shaft 86 is journaled at its respective front and rear ends by bracket 87 and housing 88 on frame 10. Drum 83 is connected to shaft 86 for rotation therewith, and drum 84 is journaled thereon and is adapted to be clutched thereto.

Controllable clutch means are provided for the rear lift mechanism to render said mechanism operative or inoperative, and brake means are associated therewith to prevent undesired movement thereof. Drum 84 (Fig. 6), at its front end, has integral toothed clutch element 91 adapted for engagement with clutch element 92 slidably and non-rotatably engaged with splined portion 93 of shaft 86. Clutch element 92 is urged into engagement with clutch element 91 by spring 94, and can be disengaged therefrom by operation of lever 96 having its forked lower end pivoted on pin 97 (Figs. 5 and 6) in link 98 which is pivotally connected at its other end to bracket 99 on frame 10. The forked lower portion of lever 96 has opposite apertures to receive trunnions 101 on opposite collar members 102, secured together by suitable bolts and engaging an annular groove (Fig. 6) in clutch element 92. Thus, by oscillation of lever 96, clutch elements 91, 92 can be adjusted to engaged or disengaged position.

Brake means are provided for selectively maintaining the rear lift mechanism in adjusted position when the mechanism is disconnected from power shaft 86. Freely journaled hoist drum 84 (Fig. 6) has brake drum portion 106 engaged by brake band 107 (Figs. 5 and 6) having one end secured to bracket 99 by threaded bolt 108 having adjusting nuts 109 secured thereon. At its other end, band 107 is pivotally connected to arm 110 on shaft 111. Shaft 111 is journaled in bracket 99 and at its other end has foot pedal 112 secured thereto. Spring 113 (Figs. 5 and 6) tensioned between frame 10 and foot pedal 112 urges pedal 112 to inoperative position. When it is desired through rotation of shaft 86 to adjust the front lift mechanism 83, 82 independently of the rear lift mechanism, lever 96 (Fig. 6) is operated to disengage clutch elements 91, 92, and brake pedal 112 is operated to hold brake band 107 against brake drum portion 106. Should it be desired to lower the rear lift mechanism 84, 82 independently of the front lift mechanism, this can be readily done, even when shaft 86 is being driven, by disengaging clutch elements 91, 92 and not actuating the brake. Thus, the rear end of the plow frame 26 will lower by gravity 75 until the brake is actuated.

Shaft 86 (Fig. 6) extends within housing 88 and has worm wheel 116 secured thereon and engaging worm 117 on shaft 118. Shaft 118 (Fig. 5) extends outwardly from housing 88 and is connected to shaft 119 operated by a reversible clutch mechanism in gear box 17. As a result, a power drive can be selectively transmitted in either direction to plow lift shaft 86.

From the foregoing description, it is seen that front and rear lift mechanisms are provided for the plow, which can be operated simultaneously or independently to raise and lower the ends of the plow beam, thereby adjusting the suction of the plow. The lift mechanisms are operated by power operated control mechanism including one of hand levers 18 (Fig. 1) adjacent operator's seat 120. When desired, the control of the power operated control mechanism can be varied by operation of the clutch lever 96 and foot pedal 112.

I, therefore, claim as my invention:

1. In an elevating grader, an earth-engaging tool, means for adjustably supporting said tool at spaced points, and means for adjusting said supporting means including a power shaft extending substantially the entire distance between said spaced points and connected adjacent the ends thereof to said supporting means, a releasable connection between said power shaft and one of said supporting means, and manipulable means for preventing movement of said one of said supporting means when said releasable connection is disabled.

2. In an elevating grader, a frame, a plow construction including a plow and a longitudinally extending beam, a longitudinal shaft on said frame, front and rear connections from said shaft to said beam, one of said connections including a clutch, and friction brake means for preventing movement of said connection when said clutch is disabled.

3. In an elevating grader, a frame, a plow construction including a plow and a longitudinally extending beam, a longitudinal shaft on said frame, front and rear connections from said shaft to said beam, means for operating said connections to raise and lower the respective ends of said beam, means for disabling one of said connections, and friction brake means for preventing movement of the end of said beam associated with said one of said connections.

4. In an elevating grader, a plow, a frame, means for adjustably supporting said plow on said frame, power operated control mechanism for adjusting said supporting means, and means for varying the control of said control mechanism including clutching means and a friction brake associated with said supporting means and operable independently of said control mechanism.

5. In an elevating grader; a frame; a plow construction, including a longitudinally extending beam, and a plow supported thereon; a longitudinally extending power shaft journaled on said frame; lift means from the front of said shaft to said beam, including a drum fixed to said shaft, and a chain connected to said drum and to said beam; and lift means from the rear of said shaft to said beam, including a second drum journaled on said shaft, a chain connected to said drum and to said beam, a releasable connection between said drum and said shaft, and control means for said releasable connection.

6. In an elevating grader; a frame; a plow construction, including a longitudinally extend-

- ing beam, and a plow supported thereon; a longitudinally extending power shaft journaled on said frame; lift means from the front of said shaft to said beam, including a drum fixed to said shaft, and a chain connected to said drum and to said beam; and lift means from the rear of said shaft to said beam, including a second drum journaled on said shaft, a chain connected to said drum and to said beam, a clutch connection between said drum and said shaft, control means for said clutch connection, a brake drum portion associated with said second drum, and brake means associated with said brake portion.
7. In an elevating grader, a plow support, spaced adjustable connections to said plow support, power operated means for adjusting said
- 5 connections together, and means for disconnecting one of said connections from said power operated means and rendering said one connection capable of adjustment independent of said power operated means.
8. In an elevating grader, a plow support, spaced adjustable connections to said plow support, operating means including a rotatable shaft upon which both of said connections are mounted for adjusting said connections together, 10 and means for disconnecting one of said connections from said shaft and rendering said one connection capable of adjustment independent of said operating means.
